UNITED STATES PATENT OFFICE.

PETER LOEWEN, OF REINLAND, MANITOBA, CANADA.

LIFE-BOAT.

1,206,873.

Specification of Letters Patent.

Patented Dec. 5, 1916.

Application filed May 6, 1916. Serial No. 95,926.

To all whom it may concern:

Be it known that I, PETER LOEWEN, a subject of the King of England, residing at Reinland, in the Province of Manitoba and 5 Dominion of Canada, have invented certain new and useful Improvements in Life-Boats, of which the following is a specification.

The present invention relates to new and useful improvements in inclosed life-boats 10 and the primary object of my invention is to provide in a compact, strong and durable and safe structure, an improved life-boat.

Another object of my invention is to provide a life-boat of the class described having improved steering means associated therewith, said steering means being adapted to be moved into and out of operative position when desired.

A further object of my invention is to 20 provide a life-boat of the class described having side portions thereof formed to accommodate propelling means such as oars or the like.

A still further object of my invention is 25 to provide improved ventilating means for the boat and improved entrance and exit means therefor.

Other objects and advantages to be derived from the use of my improved life-boat will appear from the following detail 30 description and the claims, taken with an inspection of the accompanying drawings, in which:—

Figure 1 is a side elevation of a life-boat 35 embodying the improvements of my invention. Fig. 2 is a vertical sectional view taken on the line 2—2 of Fig. 1. Fig. 3 is an enlarged vertical sectional view taken on the line 3—3 of Fig. 1. Fig. 4 is a vertical 40 sectional view of an improved ventilator which I employ. Fig. 5 is a fragmental sectional view of the entrance member partly open showing the improved latch means therefor. Fig. 6 is an enlarged detail elevational view of the propelling attachment. Fig. 7 is an enlarged vertical sectional view 45 of the stern of the boat showing my improved collapsible rudder. Fig. 8 is a longitudinal sectional view taken on the line 8—8 of Fig. 7. Fig. 9 is a similar view taken on the line 9—9 of Fig. 7. Fig. 10 is a fragmental sectional view of a modified form of seat for use in my improved life-boat.

50 Referring more particularly to the drawings, wherein similar characters of reference

designate like and corresponding parts throughout the various views, 1 designates the hull of my improved life-boat, the same being formed substantially semi-cylindrical and having a top section 2 riveted as at 3 to said section 1. The section 1 is provided on the forward end with an upwardly extending shield portion 4, the portion 4 being provided with a removable frame 5 having a port hole 6 therein to permit the pilot or other persons steering the boat to obtain a clear view ahead. The hull 1 is provided with a plurality of port holes 7 of the construction described in detail hereinafter, 60 certain of said port holes being arranged adjacent the juncture between the bottom and top sections of the boat. A pair of loops 8 are carried at the forward and the rear ends of the hull 1 whereby the boat 65 may be hoisted to position on a ship.

Entrance and exit means is provided on the top section 2 in the form of a turret 9 riveted at 10 to said section and having a hinged closure 11 permitting ingress and 70 egress of the passengers. I provide means for sealing the closure 11 said means being best shown in Fig. 5 and including a rod 12 carried by the closure 11 and having the head 13. A lever 14 pivoted at 15 on the 75 bracket 16 carried by the section 2 is formed with a slot 17 for engaging with the head 13 when the closure is in the closed position. A pair of ladders 18 are mounted on the upper portion 2 of the boat to permit passengers to climb aboard the boat after the 80 same has been launched. A ladder 18' is provided inside of the boat by means of which the passengers may gain the floor or deck 22 from the entrance. Hand rails 19 85 may be provided on the top section 2 for an obvious purpose. The bottom section 1 of the boat is formed with a tapering portion 20 forming a keel. This prevents undue 90 rolling of the boat in a heavy sea.

The interior arrangement of the life-boat is best shown in Figs. 2 and 3. For the accommodation of passengers, I provide seats 21 arranged along the side portions of the boat on a deck or floor 22. An aisle is thus 95 formed between the rows of seats 21 permitting those in charge of the boat to pass to one end of the boat from the other without inconvenience. Food and water compartments 23 may be arranged beneath the 100 seats 21 as best shown in Fig. 3. Ballast tanks 24 may be arranged beneath the deck 105 110

22 for an obvious purpose. A bilge pump 25 having an outlet 26 serves the purpose of removing water from the space beneath the deck 22.

5 A plurality of ventilating members 28 are provided in the top section 2, said ventilating members being best shown in Fig. 4. Referring to Fig. 4, the ventilator preferably comprises a supporting cone 29 riveted at 30 to the inner wall of the section 2. The cone is provided with a plurality of openings 31 permitting ventilation. A threaded bushing is carried by the lower end of the cone 29 and a screw having a hand wheel 34 on the free end thereof engages in said bushing. A closure member 35 is carried by the upper end of the screw 33 having universal connection therewith by means of a ball and socket joint 36. The closure member 35 is adapted to engage an annular angle iron 37 when in closed position and it will thus be seen that the ventilation of the boat may be controlled from the interior thereof by rotating the screw 33 to raise and lower the closure member 35. The universal joint 36 insures even engagement of the closure member with the angle iron 37.

30 For the accommodation of luggage in the form of clothes and the like for the passengers, I provide the compartment 39 formed in the section 2, by means of the partition 40 extending transversely of said section 2 and longitudinally of the boat. Double doors 41 hinged at 42 serve to permit access to the compartment 39. A latch 43 serves to maintain the doors in closed position.

35 In order to propel my improved life-boat, the port holes 7 are preferably removably arranged in the section 1, whereby to accommodate the oars 45, said oars having associated therewith annular bearing members 46 retainable in position by means of the rings 47, a flexible water excluding web 48 being connected with oars and with said rings 47. It will thus be seen that free movement of the oar is permitted without the danger of ingress of the water or the like.

50 Referring now to the steering mechanism, of my improved life-boat, best shown in Figs. 7 to 9, I form the lower portion 1 of the boat with a chamber 49, the water excluding partition 50 forming said chamber. 55 The object of my improved collapsible rudder is to enable the life-boat to be packed or stored on a vessel in a minimum amount of space, and at the same time to provide a rudder which would when in operative position, serve to effectively control the course of the life-boat. The rudder proper designated 51 is provided with a casting 52 pivotally connected at 53 with the rudder stock 54 which is in turn journaled in a 60 rudder port 55 formed in the partition 50.

A tiller 56 may be detachably carried by the upper end of the rudder-stock for steering the boat from the rear end. However, the preferred arrangement of the steering mechanism includes a pulley 57 carried by 70 and rotatable with the rudder-stock and over which is trained the steering cable 58, said steering cable extending lengthwise of the boat and communicating with the steering wheel 59 mounted in the forward portion 75 of the boat. Suitable idlers 60 serve to accommodate the cable and guide the same adjacent the turns. I provide means for shipping and unshipping the rudder, that is, means for swinging the rudder from the 80 position shown in Fig. 7 to the operative position indicated in dotted lines in the same figure. Said rudder shifting mechanism comprises preferably a rod 61 pivotally connected at 61' to a bracket member 85 62 which is pivotally connected as at 62 with the rudder 51 and passing through a water-tight packing device 63 carried in the partition 50. The inner end of the rod 61 is pivotally connected at 64 with a lever 90 65 mounted at 66 and having the locking member 67 engageable with the recesses 68 of a segment 69. When the lever is swung rearwardly and forwardly, the rudder 51 will be moved to a position clear of the 95 stern portion of the boat into the dotted line position ready for use. A plurality of stops 70 are formed on the stern of the boat for engagement with a flange member 71 carried by the rudder whereby the outward 100 movement of the rudder will be limited. Of course, it will be understood that the stop member 71 does not interfere with the proper rotation of the rudder to steer the boat. The stop member 71 is carried by 105 the rudder by means of loops 72 engaging through stop member secured therein by means of pins 73. This engagement permits renewal of the stop member in the event of 110 breakage or the like.

It will be seen that my improved life-boat may be installed on large vessels and in the event of sinking of the large vessel, the entrance member 11 may be opened and the passengers permitted to enter the life-boat. 115 The entrance member is now closed and when the vessel sinks, the life boat will float free therefrom. Should any of the passengers be thrown into the sea, if an accident occurs and are unable to reach the life-boat, these passengers may be taken up later, the ladders 18 permitting persons in the water to climb aboard the life-boat. I do not limit myself to any particular shape of the boat nor to any particular size or material employed in building the boat, since this can be best determined from reducing the device to actual practice.

120 Referring to Fig. 10, I have provided a modified form of seat arranged transversely 130

of the boat and comprising a seat board 75 fastened to the sides of the bottom 1 of the boat. A vertically arranged strengthening board 76 is arranged beneath said seat board along the longitudinal center thereof and it will be apparent that this form of seat materially strengthens the hull of my improved life-boat.

From the above description taken in connection with the accompanying drawings, it is thought that a clear and comprehensive understanding of the construction, operation, and advantages of my invention may be had, and while I have shown and described my invention as embodying a specific structure, I desire that it be understood that I may make such changes in said structure as do not depart from the spirit and scope of the invention as described.

Having thus fully described my invention, what I claim as new and desire to secure by Letters Patent, is:—

1. A life-boat comprising a normally closed shell, a casing formed in the stern portion of said shell and opening outward, a rudder shaft journaled in said casing, a rudder carried by said rudder shaft and movable with relation thereto, said rudder being normally disposed entirely within said casing, means connecting said casing and rudder for moving the latter with relation to the former, and means carried by said casing and rudder for limiting the extent of said movement.

2. A life-boat comprising a normally

closed shell, a casing formed in the stern portion of said shell and opening outward, a rudder shaft journaled in said casing, a rudder carried by said shaft, a lever carried by said casing and connected to said rudder for moving the same longitudinally of said casing, and means carried by said casing and rudder for limiting their relative movement.

3. A life-boat comprising a normally closed shell, a casing formed in the stern portion of said shell and opening outward, lugs carried by said casing and projected into the open portion thereof, a rudder shaft journaled in said casing, a rudder carried by said shaft, a plate hinged to the inner edge of said rudder for engagement with the said lugs to limit the outward movement of said rudder, and a lever carried by said casing and connected to said rudder for moving the same longitudinally of said casing.

4. A rudder for ships, including in combination with a ship's hull having the chamber at the stern thereof open to the sea, a rudder section, a rudder-post, said section being pivotally connected to said post, means for rotating the post, at times, means pivotally associated with said rudder and extending within the hull to swing the rudder into and out of said chamber, and stop means associated with said rudder.

In testimony whereof, I affix my signature hereto.

PETER LOEWEN.
